UNITED STATES PATENT OFFICE.

WILLIAM STRASBURGER AND JOSEPH HERMANN, JR., OF CINCINNATI, OHIO.

DESIGN FOR A ROLLING PIN.

Application filed April 6, 1922. Serial No. 1,614. Term of patent 3½ years.

To all whom it may concern:

Be it known that we, WILLIAM STRASBURGER and JOSEPH HERMANN, Jr., residing at Cincinnati, in the county of Hamilton and State of Ohio, respectively, have invented a new, original, and ornamental Design for Rolling Pins, of which the following is a specification, reference being had to the accompanying drawings, forming a part hereof.

We claim:

The ornamental design for a rolling pin as shown.

WILLIAM STRASBURGER.
JOSEPH HERMANN, JR.

Witnesses:

HARRY TIERNAN,
CHRISTIAN W. TIERNAN.
